UNITED STATES PATENT OFFICE.

WILLIAM H. BARNES, OF ROCHESTER, NEW YORK, ASSIGNOR TO THE SILL STOVE WORKS, OF SAME PLACE.

DESIGN FOR A STOVE OR RANGE.

SPECIFICATION forming part of Design No. 23,687, dated October 9, 1894.

Application filed June 22, 1894. Serial No. 515,430. Term of patent 14 years.

To all whom it may concern:

Be it known that I, WILLIAM H. BARNES, of Rochester, in the county of Monroe and State of New York, have invented and produced a 5 Design for Stoves or Ranges; and I do hereby declare the following to be a specification, reference being had to the accompanying drawing showing a perspective view of a stove constructed after my design.

10 The leading features of the design consist of the configuration and ornamentation of the parts as hereinafter described and claimed.

The base A of the stove and the legs B are covered with the surface ornamentation 15 shown consisting of the beaded border a at the top, and the duplicated figures on opposite sides of the center of the front embodying the leaf like ornaments a' with central beaded mid-ribs a^2 and the central anthemion a^3 . At 20 the corners are the ornaments b which continue down upon the legs.

The body of the stove is provided at the front with the oven-door C, the fire-box door D, the ash-pit door E and the water-heater 25 panel F with the ornamental bracket G beneath the latter.

The oven-door C has the beaded border c around it, a plain surface c' and a central panel c^2 ornamented by scroll work, as shown. 30 It is further provided with the curved handle c^3 and small ornamental figures near the ends thereof.

The fire-box door D is provided with the beaded border d and the central panel with 35 the leaf-like ornament d' provided the beaded mid-rib.

The ash-pit door E is ornamented with the central oval panel e and approximately in the foci thereof are two projections e' with radiating ornamental lines or ribs extending therefrom.

The water-heater panel F has the beaded border f the rounded surface f' and the central ornamented panel f^2 .

45 The ornamental shelf H is arranged below the main oven door.

The end of the stove has the hearth or shelf J, the flange j of which extends beneath the

ash-pit door and above the shelf is the lower end panel K having the beaded border k and 50 small panels k' . Above this panel K is the name plate panel L with double reverse curved lower edge.

The feed-door M has the beaded border and draft openings m therein, the space between 55 these being ornamented as shown.

The top section of the stove comprises the central rounded smoke-pipe having the lower rounded panel N with apertures n surrounded by curved ornamental ribs, as shown. 60 Above this is the central panel O having the conventional leaf-like ornament nearly covering it and the beaded border o at the sides extending also through the lower panel N. From each side of the smoke-pipe extend the 65 horizontal panels P each having the conventional leaf-like ornaments with ogee curved beaded mid-ribs and a rosette p at their juncture, and above the panels are the side panels or brackets Q formed of open scroll-work. 70 The shelf R extends across the top of the smoke-pipe section, and the brackets Q, and above this is the top-rail S composed of ornamental scroll-work with the anthemion S' for a center piece.

75 The upper section of the stove or range is comprised within the part lettered U, and the body portion as a whole within the part lettered V.

I claim as my invention—

1. In a design for a stove or range, the design for the base, substantially as herein shown and described.

2. In a design for a stove or range, the design for the oven-door, substantially as herein shown and described.

3. In a design for a stove or range, the design for the fire-box door, substantially as herein shown and described.

4. In a design for a stove or range, the design for an ash-pit door, substantially as herein shown and described.

5. In a design for a stove or range, the design for a central panel for the smoke-pipe, substantially as shown and described.

6. In a design for a stove or range, the de-

sign for a lower panel for the smoke-pipe, substantially as shown and described.

7. In a design for a stove or range, the design for the horizontal panels P, substantially as shown and described.

8. In a design for a stove or range, the design Q for the side panel, substantially as shown and described.

9. In a design for a stove or range, the de-

sign S for the top rail, substantially as shown and described.

10. The herein described design for a stove or range, substantially as shown in the accompanying drawing.

WILLIAM H. BARNES.
